UNITED STATES PATENT OFFICE.

FREDERICK W. ZEIDLER, OF JERSEY CITY, AND CARL HALPERN, OF NEWARK, NEW JERSEY.

CANOE.

1,387,957.

Specification of Letters Patent. Patented Aug. 16, 1921.

Application filed November 13, 1920. Serial No. 423,792.

To all whom it may concern:

Be it known that we, FREDERICK W. ZEIDLER, a citizen of the United States, residing in Jersey City, county of Hudson, and State 5 of New Jersey, and CARL HALPERN, a citizen of the United States, residing in Newark, county of Essex, and State of New Jersey, have invented certain new and useful Improvements in Canoes, of which the following is a specification.

While designed more particularly for use in conjunction with the type of small, paddle controlled boats known technically as canoes, our invention is applicable to 15 hand-propelled craft generally,—the object being to stabilize navigation, mitigate lateral rocking, and prevent the capsizing of the boat in so far as possible.

The invention consists primarily in the 20 use of a transversely movable seat for the occupant of the boat, which seat is so mounted as to adapt itself automatically to the motion of the craft and in such manner as to render the weight of the person occupying 25 the seat available for the purpose of "trimming the boat" by neutralizing any tendency of the craft to deviate from proper alignment; and secondarily the invention consists in the use, in conjunction with the movable 30 seat of the character designated of gravity controlled means which prevent the seat from moving in the wrong direction.

In the accompanying drawings,

Figure 1, is a perspective view of our 35 equilibrious seat and the adjacent portion of a canoe in which it is mounted;

Fig. 2, is a transverse section of the canoe, showing our equilibrious seat and mount in 40 rear elevation, and illustrating the function thereof;

Fig. 3, is a top view of our equilibrious seat and adjacent portion of the canoe;

Fig. 4, is a section taken upon plane of 45 line 4—4, Fig. 3, showing our seat and its mount in front elevation;

Fig. 5, is a section taken upon plane of line 5—5, Fig. 4;

Fig. 6, is a section taken upon plane of line 6—6, Fig. 5;

Fig. 7, is a section taken upon plane of 50 line 7—7, Fig. 5;

Fig. 8, is a perspective view of the keel standard and base.

C, represents a canoe or small boat of any

desired or well known shape and construction,—c, being the gunwale to and between which the ends of our transversely movable seat S, are resiliently attached, as by coiled springs s, or equivalent means which tend constantly to centralize said seat as related to the longitudinal axis of the craft.

The seat S, is rigidly secured medially to a post P, the lower end of which is pivotally supported on a fixed fulcrum f, mounted on the base of a standard b, integral with the base plate B, which is affixed to the flooring of the boat.

Pivotaly suspended at r, upon the upper end of the seat post P, is a foot rest R, which is free to swing, pendulum like, independent of, but upon, said seat post P,—as shown in Fig. 2. The lateral play or extent of movement of the seat post P, and hence of the seat itself, is governed by a pin b^x, affixed to the upper part of the standard b, 75 projecting into a slot p², in the seat post P,—said slot p², being concentric with the fulcrum f, and the ends of the slot p², constituting shoulders which limit the sway of the seat in either direction.

The seat post P, is also formed with cross arms p³, p³ on which are pivotally suspended gravity pawls p⁴, p⁴, the lower extremities of which just clear, coincidental shoulders b', b', on the base plate B, when the said post is perpendicular as related to said base plate, as in all but Fig. 2, of the drawings. When the vessel tilts laterally however it raises one or the other of these retention shoulders b', b', into position to engage with 90 and prevent further gravitation of its particular pawl p⁴, so that in case the occupant of the seat were to lean in the wrong direction, or toward the lower side of the boat, tending to rock the seat in that direction, the 95 gravity pawl p⁴, on that side would engage with its detent shoulder b', and by preventing the shifting of the center of gravity to the lower side of the canoe, obviate all danger of the capsizing thereof. In other words, the gravity pawls insure the maintenance of the center of gravity on the higher side of the boat when the latter rocks laterally.

s^x, s^x, are cross bars on the upper side of 105 the seat S, which enable the occupant to centralize his position thereon.

To enable the occupant of the seat S, to

balance himself conveniently and comfortably in conformity with the lateral rocking of the boat we provide the pendulous foot rest R, which admits of the swinging 5 of the feet in a direction opposite to the inclination assumed by the upper part of the body, while at the same time by reason of its pivotal connection with the seat post, adding the weight of the feet and legs to 10 the aggregate weight positioned beyond the perpendicular line v, of the standard b, when the boat is rocked in either direction, so that the total weight of the occupant of the the seat is available in automatically 15 trimming and correcting the alinement of the craft in the manner above set forth.

In order to limit the extent of lateral movement of the foot rest R, its suspending member R', may be formed with an elongated 20 slot r', through which the pin b^x, on the standard b, projects, as shown more particularly in Figs. 5 and 7, thus, allowing the foot rest to swing on its pivotal support r, while limiting its extent of motion in either 25 direction, and at the same time insuring a swing opposite to that assumed by the seat post P, as related to the fulcrum f, as will be seen by reference to Fig. 2.

Of course the springs s, s, or equivalent 30 retractile means, perform an important function in conjunction with the pivotally mounted seat in absorbing and neutralizing the strain, and stabilizing the motion of the craft,—tending constantly, as they do, 35 to maintain the seat in medial position with its supporting post P, in substantial alinement with the perpendicular standard b.

Thus mounted and equipped, our stabilizing seat affords effectual protection against 40 any tendency to capsize or rock excessively, even in relatively rough water and weather, and adds materially to the safety, comfort and convenience of the navigator.

What we claim as our invention and desire to secure by Letters Patent is,

1. In combination with a boat of the character designated, a seat movably mounted, and elastic resilient means tending to main-

tain the seat in normal position, for the purpose described.

2. In combination with a boat of the character designated, a seat mounted on a pivotally supported post, and elastic resilient means tending to maintain the seat in normal position, for the purpose described.

3. In combination with a boat of the character designated, a seat rigidly mounted on a pivotally supported post and elastic resilient means tending to maintain the seat in normal position, for the purpose described.

4. In combination with a boat of the character designated, a seat mounted on a pivotally supported post, elastic resilient means tending to maintain the seat in normal position and a foot rest pivotally and pendulously supported on said seat post, for the purpose described.

5. In combination with a boat of the character designated, a seat movably mounted, elastic resilient means tending to maintain said seat in normal position, and means for limiting the extent of motion of said movably mounted seat, for the purpose described.

6. In combination with a boat of the character designated, a seat mounted on a pivotally supported post, elastic resilient means tending to maintain the seat and post in normal position, and a fixed standard adjacent to said seat post formed with means for limiting the movement of said post, for the purpose described.

7. In combination with a boat of the character designated, a seat mounted on a pivotally supported post, elastic resilient means tending to maintain the seat and post in normal position, a foot rest pivotally and pendulously supported on said seat post, and a fixed standard adjacent to said seat post and formed with means for limiting and prescribing the relative movements of said seat post and said foot rest.

FREDERICK W. ZEIDLER.

CARL HALPERN.
